UNITED STATES PATENT OFFICE

SOREN C. JENSEN, OF PRESQUE ISLE, MAINE

BARREL CARRYING DEVICE

Application filed November 26, 1930. Serial No. 498,473.

This invention appertains to means for facilitating the carrying and handling of barrels and is of the type illustrated in my application for patent entitled "Barrel carrying device", executed under date of September 29, 1930, Serial Number 491,629.

The primary object of my present invention is to provide a barrel carrying device of the type illustrated in my pending application above referred to, in which novel means is provided for forming the barrel carrying device to permit the effective engagement thereof with the barrel and to permit the effective gripping of the device.

15 With these and other objects in view, the invention consists in the novel construction, arrangement and formation of parts, as will be hereinafter more specifically described, claimed, and illustrated in the accompanying drawing, in which drawing:—

Figure 1 is a perspective view of a further form of my barrel carrier.

Figure 2 is a horizontal section through the barrel carrier of the type illustrated in Figure 1.

Figure 3 is a fragmentary perspective view illustrating a modified form of my barrel carrier.

In the drawing I have illustrated my barrel carrier which is generally indicated by the reference character P, and which can be formed of sheet metal suitably fabricated. In this form of my invention I provide a pair of side plates 189 and 190, which are of like form. These plates are provided with longitudinally extending slots 191 adjacent to their rear ends and with enlarged openings 192 for lessening the weight thereof. The front plates are also cut away to provide at their upper ends forwardly projecting prongs 193 for engaging the side of the barrel and upwardly projecting hooks 194 for engaging under the rim of the barrel. These plates can be connected together by cross bars 195 and 196, and by a lower handle 197. This handle may constitute a hand grip 198 and an axially extending bolt 199 employed for connecting the side plates and hand grip together. The barrel carrier P can also be provided with an adjustable handle, which

may include a hand grip 200, having extending axially therethrough a bolt 201, the head of which engages one plate 190 and the winged nut 202 threaded on the bolt engages the other plate.

In Figure 3 I have shown a slightly modified form of my invention which is illustrated in Figures 1 and 2, and in this form I provide pairs of upper and lower cross bars 203 and 204 which are connected together by vertical side bars 205 and 206. The inner terminals of the upper and lower pairs of cross bars 203 and 204 carry vertically extending wire rods 207, the upper ends of which are integrally connected together by a cross piece or bight portion 208. The lower ends of the wire side bars 207 have formed thereon hooks 209 for engaging under the rim of the barrel. The forward ends of the upper pair of cross bars 203 have formed thereon pointed prongs 210 for engaging the sides of the barrel. An adjustable handle 211 is provided which can be of the same type as the handle 200 shown in Figures 1 and 2 and the bolt 201 thereof extends between the side plates 205 and 206.

Changes in details may be made without departing from the spirit or the scope of this invention, but:—

What I claim as new is:

1. A barrel handling and carrying device comprising a pair of like side plates having forwardly projecting barrel engaging prongs on their upper ends and upwardly projecting hooks on their lower ends, said side plates being provided with vertically extending slots, a bolt extending through the slots, a hand grip formed on the bolt, a second bolt extending through the side plates having a hand grip thereon, and upper and lower brace bars connecting the side plates together.

2. A barrel handling and carrying device comprising a pair of side members, forwardly projecting barrel-engaging means carried by said side members near the upper ends thereof, and upwardly projecting hooks carried by the lower ends thereof, said side members provided with vertically extending slots, a bolt extending through said slots, an en-

larged hand grip formed on said bolt and having the ends of said hand grip abutting the inner faces of said side members, and means engaging said bolt for locking said hand grip in an adjusted position within the length of said slots.

In testimony whereof I affix my signature.
SOREN C. JENSEN.
